(57) **CLAIM**

The ornamental design for a cardio core exercise device as shown and described.

DESCRIPTION

FIG. 1 is a bottom view of a cardio core exercise device of my new design.

FIG. 2 is a top view of the cardio core exercise device.

FIG. 3 is a left-side view of the cardio core exercise device.

FIG. 4 is a right-side view of the cardio core exercise device.

FIG. 5 is a front view of the cardio core exercise device; and,

FIG. 7 is a bottom perspective of the cardio core exercise device.
